UNITED STATES PATENT OFFICE.

ALBERT J. DEVAUD, OF SCHENECTADY, NEW YORK, ASSIGNOR TO GENERAL ELECTRIC COMPANY, A CORPORATION OF NEW YORK.

TURBINE-NOZZLE DIAPHRAGM.

Application filed November 21, 1925. Serial No. 70,625.

In the manufacture of elastic fluid turbines, it is customary to split the casing and diaphragms in the plane of the axis of the machine, and since nozzle partitions extend 5 angularly, this means that the partitions crossing the plane of the split are cut in two. The cutting in two of these partitions weakens them, particularly their forward or discharge ends, and in the case of diaphragms 10 having nozzle partitions of considerable radial length it has been found necessary to provide struts or braces for the discharge ends of the split partitions to give additional strength to them.

15 In connection with the operation of certain turbine bucket wheels, vibrations occurred which could not be attributed to any known causes. In the particular instances, the wheels had been tested in accordance 20 with the methods set forth in the patents to Campbell, Numbers 1,502,903 and 1,502,904 dated July 29, 1924 and they should have been entirely free from vibration at the normal operating speeds. However, such was 25 not the case.

After careful investigation, I discovered that in the particular instances, the vibrations were due to the disturbances set up in the elastic fluid flow by the above-referred 30 to struts or partitions. The buckets when passing through the regions of disturbed flow were subjected to a slight shock or impulse, and in the particular instances the periods were such as to be effective in producing and maintaining vibrations.

To overcome the above trouble, I found it necessary to omit entirely the struts or braces for the cut nozzle partitions, and in order to be enabled to do this and still have the 40 required nozzle partition strength, I now split the diaphragm along lines between nozzle partitions rather than on lines through the nozzle partitions. By this means I avoid altogether any cut nozzle partitions. Preferably I split the diaphragm along straight angular lines rather than on curved lines as this makes machining of the parts easier.

50 In the drawing, Fig. 1 is a perspective view of a turbine nozzle diaphragm embodying my invention, the two halves of the diaphragm being shown separated; Fig. 2 is a face view showing the halves of the dia-

phragm together, and Fig. 3 is a detail view 55 of the edge of the diaphragm.

Referring to the drawing, 1 indicates the upper half of a turbine nozzle diaphragm, 2 the lower half, and 3 the nozzle partitions. The halves of the diaphragm are held in alignment by keys 4 which fit into keyways 5 and by suitable fasteners 6. The nozzle partitions directly adjacent to the horizontal plane through the center of the diaphragm are indicated at 7 and 8 and as will be clear 60 from the drawing, the line of parting between the two halves of the diaphragm runs between these nozzle partitions. As shown the line of parting is in two angular planes 65 9 and 10 which lie entirely between the adjacent nozzle partitions 7 and 8.

70 By my invention I avoid cut nozzle partitions and hence am enabled to do away entirely with braces or struts between any of the nozzle partitions. As a result, the elastic fluid flow from the entire ring of nozzles is 75 even and uniform and hence is not likely to be a means of causing vibrations.

What I claim as new and desire to secure by Letters Patent of the United States, is:

1. A split nozzle diaphragm having a continuous ring of angularly-extending nozzle partitions which overlap one another, characterized by the fact that the split extends along lines between adjacent nozzle partitions whereby the cutting of any nozzle partition is avoided.

80 2. A split nozzle diaphragm having a continuous ring of angularly-extending nozzle partitions which overlap one another, characterized by the fact that the split extends along planes which are at an angle to each other and which lie between adjacent nozzle partitions whereby the cutting of any nozzle partition is avoided.

85 3. A split nozzle diaphragm having concentric radially spaced portions connected solely by a continuous ring of angularly-extending duplicate-nozzle partitions which overlap one another, characterized by the fact that the split extends along lines between adjacent nozzle partitions whereby the cutting of any nozzle partition is avoided.

90 In witness whereof, I have hereunto set my hand this 20th day of November, 1925.

ALBERT J. DEVAUD.
